UNITED STATES PATENT OFFICE.

JOHN ROGERS, OF NEW YORK, N. Y.

DESIGN FOR A GROUP OF STATUARY.

Specification forming part of Design No. 5,143, dated July 25, 1871.

To all whom it may concern:

Be it known that I, JOHN ROGERS, of the city, county, and State of New York, have invented and produced a new and original Design for a Group of Statuary.

The nature of my design is fully represented in the accompanying photographic illustrations.

The group is called "Rip Van Winkle Returned," and shows Rip as an old man, with long hair and beard, standing in his ruined gate-way. With his left hand he is lifting his hair from his

eyes and gazing round, trying to recognize his old homestead, while his dog skulks away from him over the stone wall at his right.

I claim as my invention—

The design for a group of statuary, as shown in the above specification.

JOHN ROGERS.
